UNITED STATES PATENT OFFICE.

SOLOMON S. WHITMORE, OF BALTIMORE, MARYLAND, ASSIGNOR OF ONE-HALF TO JOHN NEUMANN, OF SAME PLACE.

DUMPING-WAGON.

SPECIFICATION forming part of Letters Patent No. 440,936, dated November 18, 1890.

Application filed July 14, 1890. Serial No. 358,745. (No model.)

To all whom it may concern:

Be it known that I, SOLOMON S. WHITMORE, a citizen of the United States, residing at Baltimore city, in the State of Maryland, have 5 invented new and useful Improvements in Dumping-Wagons, of which the following is a specification.

My invention relates to dumping-wagons for coal and similar articles; and it has for 10 its objects to provide improved means for dumping and delivering the load and for supporting the load during transportation.

To this end it consists in the improved construction and arrangement or combination of 15 parts, hereinafter fully disclosed in the description, drawings, and claims.

In the accompanying drawings, Figure 1 represents a side elevation of my improved 20 dumping-wagon, showing the box or body and the derrick lowered; Fig. 2, a side elevation of the same, showing the derrick and the box or body raised; Fig. 3, a longitudinal vertical section of the same, showing the box lowered and tilted and the chute extended; Fig. 4, a 25 transverse vertical section of the same taken through the swiveled chute of the body and looking forward; Fig. 5, a bottom plan view of the body; Fig. 6, a perspective view of the swiveled chute. Fig. 7 is a horizontal section of the same. Figs. 8 and 9 are enlarged 30 sectional views of the joining ends of two chute-sections. Fig. 10 is a vertical section of the swiveled chute, and Fig. 11 is a bottom view of the same; Fig. 12, an enlarged detail 35 view of the pawl and brake mechanism for the hoisting-windlass.

In the drawings, the numerals 11 indicate 40 the two sills which form the bed of the wagon, and are secured to and supported by the bolsters 2, the axles 3 and 4, and the wheels 5. The upper edges of said sills are rounded off or beveled upon their inner sides at 6 to form 45 a perfectly-fitting seat for the box or body 7 of the wagon. Said body is formed preferably of sheet metal, and oblong or elliptical in cross-section, with an open top. This shape of sheet-metal body, braced at the corners by interior braces 8, gives strength and comparatively great carrying capacity. Stops or 50 blocks 9 are formed upon the rounded sides of the box and rest upon the upper edges of

the sills, and stops 10, upon the upper edges of the sills and projecting between the central and end stops 9 of the box, serve to prevent longitudinal sliding movement of the box 55 upon the sills. (See Fig. 1.)

A discharge-spout 11, cylindrical at its end 12, and partly cylindrical at its upper portion, where it merges into the tail-gate 13 of the box, projects downward and slightly rearward 60 from the rear end of the bottom of the box, and is formed with a flange 14 at its lower edge. A ring 15, Fig. 6, fits and turns upon the lower cylindrical portion 12, Fig. 5, of the discharge-spout, being retained upon the same 65 by the flange 14, and said ring is provided with two diametrically-opposite laterally-projecting trunnions or pivots 16, upon which a short inner chute-section 17 is pivoted at about the middles of its upwardly-curved 70 sides, and has both a swiveling and tilting movement. Said chute is formed with a flat bottom and with outwardly-bulging curved sides, which terminate at their upper edges in vertical flanges. A chute-section 18 fits 75 and slides upon said inner chute-section having correspondingly-shaped bottom and sides, and another chute-section 19 fits and slides over said section 18, Fig. 7. The forward end of the first telescoping chute-section 18 is 80 formed with an upwardly-bent stop 20, which may bear against the forward end of the inner short chute-section 17, Figs. 2 and 3, and the rear end of the bottom of said section 18 is 85 formed with two transverse slots 21, having their forward edges slightly struck up and 90 their rear edges slightly struck down, so as to be engaged by two corresponding spring-tongues 22, which are cut out in and struck up from the bottom of the forward end of the outer telescoping chute-section, so as to form stops for said section when it is drawn out to the extreme limit, Figs. 7 and 8.

A partition or gate 23 is pivoted in the middle of the box by a rock-shaft 24, journaled 95 in the sides of the box and provided with a handle 25 or crank at one end, by means of which it may be rocked. The lower edge of said gate, which corresponds in shape to the cross-section of the box, bears against stops 100 26 in the bottom of the box, Fig. 4.

A gate or valve 27, Figs. 4 and 10, having

a semicircular rear edge 28, slides in longitudinal ways 29 under the bottom of the wagon and cuts off the lower open cylindrical end of the discharge-spout. The legs of a bail 30 are secured to the side edges of said cut-off valve or gate and slide in longitudinal bearings 31 under the bottom of the box. A removable rod or lever 32, having a hooked end, may have its fulcrum in an eye or bail 33 upon the tail-gate of the box, and may bear either against the outer or inner side of the cross-bar of said bail 30 for the purpose of pushing in or drawing out said cut-off valve or gate to open or shut the same.

15 Two longitudinal slightly outwardly-diverging guide bails or rods 34 are secured under the bottom of the box, and the telescoping chute-sections may be slid forward upon said bails and supported by them when not in use, Figs. 3, 5, and 8.

Two legs 35 of a folding derrick are pivoted upon two laterally-projecting studs 36 upon the forward ends of the sills of the wagon, and are connected at their upper ends by a trans-

25 verse rod 37. Two movable legs 38 of the derrick are pivoted at their upper ends upon said transverse rod and have their lower ends pivoted to blocks or boxes 39, which slide upon two track-rods 40 secured to the sills. The 30 forward ends of said track-rods are secured to the studs 36 and curve downward in the arc of a circle, and after describing about a quadrant of a circle they are carried rearward in a slightly upwardly-inclined direction.

35 The ends of two ropes or chains 41 are secured to the forward and rear ends of said boxes 39, and the ropes are carried around guide-pulleys 42 and 43, journaled in the forward and rear ends of the sills and around 40 drums 44 upon a shaft 45, transversely journaled under the middle of the sills and provided with a crank 46, said ropes or chains being secured at their middle to said drums and winding upon and off from 45 said drums. It is obvious that by revolving said shaft and drums by means of the crank the lower ends of the movable derrick-legs may be drawn rearward or forward upon the track-rails, raising or lowering the 50 derrick. A shaft 47, having a crank 48 at one end, is journaled under the sills near their forward ends, and has two drums 49 secured upon its ends outside of the sills. Two ropes or chains 50 are secured to said drums, to the 55 cross bar or rod 37 at their other ends, and pass around sheaves 51, Fig. 1, journaled in cases or boxes 52 upon the inner faces of the sides of the box, and upon the rock-shaft 24 of the gate 23, and around sheaves 53, Fig. 60 3, journaled upon said cross bar or rod 37.

It is obvious that when the derrick is raised and the shaft and drums 47 49 are revolved the wagon box or body may be raised from or lowered to the sills, so as to elevate 65 it to the desired height for dumping. A ratchet-wheel 54, Fig. 12, is secured upon the crank-shaft 47, and is engaged by a pawl or

shoulder 55 upon the lower edge of a lever 56, which is fulcrumed upon the side of one of the sills to the rear of the crank-shaft 47. A 70 brake-lever 57 is fulcrumed upon the same pin or bolt 58, as said pawl-lever 55 56 outside of the same, and bears with its friction portion against a friction-disk 59, upon the crank-shaft 47, serving to control the speed 75 of descent of the wagon-box, Fig. 12. Two turn-buttons 60 and 61 are eccentrically pivoted beneath the outer portions of said levers, and may, when turned up, hold the same from engagement, respectively, with the ratchet- 80 wheel and the friction-disk.

Two pairs of offsets or shoulders 62 are secured upon the sides of the wagon-box near the front and rear ends of the same, and serve to ride upon the legs 35 and 38 to guide 85 the box to a proper seat with its stops or blocks 9 in their proper positions in relation to the stops 10 upon the sills, when the box is lowered. The rear pair of offsets or shoulders serve also as rests for the legs of the derrick when the latter is fully lowered or 90 folded down.

Two ropes or chains 63 are secured to the wagon-box near its rear end, and are secured to a rope 64, which has a few turns around 95 the forward crank-shaft 47, is then passed over guide-pulleys 65 at the forward end of the wagon-bed, and has a weight 66 secured at its end, this rope 64 and its branches 63 and weight 66, to turn the wagon-box when it 100 is raised, preventing the heavier forward end from overbalancing the rear end and giving the box the required tilt.

For the purpose of propping up the rear end of the wagon-box when it is raised to its 105 highest point or near the same, and for the better adjustment of the tilting angle or inclination of the same for dumping, two rods 67 are provided, which may be inserted into holes 68 in the sides of the wagon-box near the rear end with their ends, which are twice bent at right angles in the shape of a bayonet, Fig. 2. The lower portions of said rods are bent into continuous rows of flat loops at 110 right angles to the rods, as shown at 69, forming notches which may be slipped over the ends of the shaft 45 for the derrick-raising windlass, or over the ends of arms 70 at the 115 sides of the wagon-box.

In practice the wagon, being loaded with 120 coal or whatever article is to be delivered, is driven to the place nearest accessible to the cellar, bin, or whatever place the coal is to be dumped into. The telescoping chute-sections are thereupon drawn out to reach from 125 the wagon to said cellar or receptacle, the swivel-ring joints for the chutes allowing the wagon to stand at almost any angle to the line of delivery. The derrick is then hoisted to its raised position by its windlass, whereupon the wagon-box may be raised to a height sufficient to cause the coal to slide freely through the chute by its gravity, and held raised by the ratchet-wheel and pawl- 130

lever upon its windlass. The wagon-box is now braced at its proper tilt or inclination, and the cut-off gate is opened by the hooked rod or lever, when the load will travel to its receptacle through the chute. If one half of the load only is to be delivered, the gate or partition at the middle of the wagon-box will retain the other half, which may be dumped at another place, or if the entire load is to be dumped the gate may be opened and admit the forward half of the load to the chute. When the discharge is finished, the box may be lowered, and will come to its correct seat upon the sills by the offsets or shoulders upon the box sliding down upon the inclined legs of the derrick. The friction-brake will control the speed of descent of said body. The derrick may now be lowered by its windlass, the chutes slid in place, and the cut-off gate closed, when the wagon is again ready for another load.

By providing the folding derrick for the wagon, the wagon-box may be raised to a considerable height, and consequently the coal may be conveyed through the chute to a considerable distance from the wagon. By providing the universal joint for the chute the coal may be delivered within a considerable arc of the circle, so that the position of the wagon with relation to the point of reception is rather immaterial, and parts of the load may be delivered without change of position of the wagon into different receptacles, such as several bins in a cellar or different cellars.

35 Two telescoping chute-sections only have been illustrated and described; but it is evident that any number of sections may be employed sufficient to convey the coal the required distance.

40 When the coal is to be dumped directly at the end of the wagon, the telescoping sections may be slid off from the short inner chute-section by sliding them forward upon the same and the short section alone used.

45 In small wagons or carts it may not be necessary to employ a windlass for raising and lowering the derrick; but this work may be done by directly pushing the movable rear legs of the derrick by hand or by means of suitable rods.

I claim as my improvement—

1. In a dumping-wagon, the combination of a wagon-bed and a dumping-body having side pulleys, a derrick mounted upon said bed independent of said body adapted to be folded and having purchase-pulleys, and cords or chains connecting said derrick-pulleys with said body-pulleys, substantially as described, whereby the body can be raised, and tilted after being raised.

2. In a dumping-wagon, the combination of a wagon-bed and a dumping-body having side pulleys, a derrick mounted upon said bed and having purchase-pulleys and cords or chains connecting said derrick-pulleys with said body-pulleys, the supports or legs of said derrick arranged to be raised and to be folded

together upon the bed independent of the body, substantially as described.

3. In a dumping-wagon, the combination, 70 with the wagon bed and box, of longitudinal track-rods secured upon said bed, a pair of derrick-legs pivoted upon one end of said bed, a pair of blocks or boxes sliding upon said track-rods, a pair of derrick-legs pivotally connected at their lower ends to said blocks or boxes and at their upper ends to the ends of said other legs, a windlass journaled in the wagon-bed, ropes or chains winding around said windlass, carried around guide-pulleys 75 at the ends of said wagon-bed and having their ends secured to said sliding blocks or boxes, and means for raising and lowering said wagon-box from the upper ends of said derrick-legs, substantially as described. 80

4. In a dumping-wagon, the combination of a pair of sills mounted upon wheels and beveled upon the upper edges of their inner sides, stops upon the upper edges of said sills, and a wagon-box having a rounded bottom fitting 90 in the beveled edges of said sills and provided with stops upon its rounded sides which rest upon the upper edges of said sills and alternate with the stops upon the same, substantially as described. 95

5. In a dumping-wagon, the combination of a discharge-spout formed with a cylindrical lower portion, a ring swiveled upon said cylindrical portion and provided with two diametrically-opposite studs, and a chute pivoted with its sides upon said studs, substantially as described. 100

6. In a dumping-wagon, the combination of a discharge-spout, a short chute-section supported beneath the same and formed with outwardly-bulging sides, two diverging guide bails or rods longitudinally secured beneath the bottom of the wagon-body, and a chute-section having outwardly-bulging sides adapted to slide upon said short chute-section and to be slid in upon and supported by said guide bails or rods, substantially as described. 105

7. In a dumping-wagon, the combination of a short discharge-chute section supported 115 beneath the rear end of the wagon-body, with a chute-section sliding upon the outer side of said chute-section and beneath the wagon-body, and formed with an upwardly-bent flange or stop at its forward end adapted to strike the forward end of said short section when said outer section is drawn out, substantially as described. 120

8. In a dumping-wagon, the combination of a chute-section having outwardly-bulged 125 sides and formed with transverse slots in the rear end of its bottom, having the forward edges struck up and the rear edges struck down, with a correspondingly-shaped chute-section sliding upon the outside of said other section and provided in the forward end of its bottom with rearwardly-projecting struck-up spring-tongues adapted to engage said slots, substantially as described. 130

9. In a dumping-wagon, the combination of a wagon-box having a discharge-spout at its rear end formed with a cylindrical lower portion and with a partly cylindrical upper portion merging into the tail-gate, a cut-off valve or gate having a semicircular rear edge and sliding beneath the bottom of said wagon-box into said spout, and a bail having its legs secured to the side edges of said valve or gate and sliding in ways or bearings upon the bottom of said wagon-box, substantially as described.

10. In a dumping-wagon, the combination of a four-legged folding derrick having pulleys at its top and supported upon the bed of the wagon, a wagon-box having pulleys at the middle of its sides, a windlass journaled beneath the bed of the wagon, and ropes or chains passed around said pulleys and wound upon said windlass, substantially as described.

11. In a dumping-wagon, the combination of a four-legged derrick having its legs supported at the forward and rear ends of the wagon-bed, stops upon the wagon-bed, a wagon-box having hoisting-ropes attached to said derrick, and having stops alternating with the stops upon the bed, and shoulders or offsets upon the sides of said wagon-box adapted to bear against and be guided by the legs of the derrick, substantially as described.

12. In a dumping-wagon, the combination of an upright derrick upon the wagon-bed, the wagon-box, a windlass and ropes raising and lowering said box from said derrick, two ropes secured beneath the rear end of said box, and a rope secured to the ends of said ropes, carried around the shaft of said windlass in the direction opposite to the windlass-rope, and provided with a weight at its other end, substantially as described.

13. In a dumping-wagon, the combination of a derrick upon the wagon-bed, a wagon-box

having means for being raised and lowered from said derrick, and formed with holes in its sides near the rear end, and rods having bayonet-shaped ends for engaging said holes, and bent or looped to form a series of notches to engage a shaft upon the wagon-bed, substantially as described.

14. In a dumping-wagon, the combination of a windlass for hoisting and lowering the wagon-box journaled in the wagon-bed and provided with a ratchet-wheel and a friction-disk, a lever fulcrumed upon the side of the wagon-bed and formed with a pawl or shoulder engaging said ratchet-wheel, a brake-lever fulcrumed concentric with said pawl-lever and bearing against said friction-disk, and two turn-buttons pivoted eccentrically beneath the outer portions of said levers and adapted to be turned up to disengage said levers from their ratchet-wheel and friction-disk, substantially as described.

15. In a dumping-wagon, the combination of a wagon-bed, a wagon-box resting upon said bed, a derrick having the ends of two legs pivoted to one end of said bed, and the ends of two legs longitudinally sliding upon said bed, a windlass journaled beneath said bed, ropes wound around said windlass, carried around pulleys at the ends of said bed and secured at their ends to the sliding ends of said derrick-legs, a windlass journaled beneath said wagon-bed, and hoisting-ropes wound upon said windlass and carried around pulleys upon said derrick and wagon-body, substantially as described.

In testimony whereof I have hereunto set my hand in the presence of two subscribing witnesses.
